UNITED STATES PATENT OFFICE.

JAMES H. BARLEY, OF SEDALIA, MISSOURI.

HARROW.

SPECIFICATION forming part of Letters Patent No. 236,292, dated January 4, 1881.

Application filed October 28, 1880. (Model.)

To all whom it may concern:

Be it known that I, JAS. H. BARLEY, of Sedalia, in the county of Pettis and State of Missouri, have invented certain new and useful Improvements in Harrows; and I do hereby declare the following to be a full, clear, and exact description of the invention, such as will enable others skilled in the art to which it pertains to make and use it, reference being had 5 to the accompanying drawings, which form part of this specification.

My invention relates to an improvement in harrows; and it consists, first, in the castings by means of which the teeth are secured to 15 the sides of the harrow-beams, and which castings have stops formed on their inner sides to catch against the upper or lower edges of the beam, and thus limit the movement of the teeth as they turn upon their pivots; second, 20 in securing to the sides of the iron beams flat-headed bolts, the heads of which are made wide and flat, so as to brace the beams, while the upper ends of the bolts pass through the cross-bars which unite the beams together; 25 third, in making a notch or recess in the lower end of each tooth, for the purpose of giving each tooth a double cutting edge or point.

Figure 1 is a vertical cross-section taken through the center of the harrow. Fig. 2 is a 30 side elevation of the harrow, and Figs. 3 and 4 are different views of the fastening device for the teeth. Fig. 5 is a plan view of the harrow complete. Fig. 6 is an end view of the harrow.

35 A represents the beams of the harrow, which are here made of angle or L-shaped iron bars, of any desired degree of width or thickness. These beams are made from angle-iron for the purpose of making the harrow as strong and 40 solid as possible, and yet not make them as heavy as solid iron bars or beams. These beams may be secured together at the ends by means of angle-shaped cross-pieces, or the cross-pieces may consist of small flat bars, which are secured to the top of the beams, as may be preferred. In order to strengthen and brace each 45 one of the angle-beams A where they are secured to the cross bars or braces, the screw-bolt C is provided with a wide flat head, d, which is 50 riveted to the vertical part of the beam A, as shown, and which flat head serves as a brace

for the whole of this vertical part. Through the horizontal part of the angle-beam are made suitable holes, up through which the screw ends of the bolts pass, and these screw 55 ends also pass through the cross-pieces which connect the beams together, and receive the nuts upon their upper ends.

The fastening device, by means of which each harrow-tooth is secured to the side of 60 the angle-beams A, consists of a casting, D, of any desired shape or size, and which has a hole through its center for the clamping-bolt F to pass through, and this bolt serves not only to hold the teeth in position against the 65 casting, but as a pivot upon which both the casting and the tooth moves. Upon the front side of this casting D is made a suitably-shaped recess, to receive the harrow-tooth H, which tooth is made from flat bars of steel, as 70 here shown, having a sharp cutting-edge upon its front and a blunt edge upon its rear, so as to adapt it for different kinds of work. The outer end of the clamping-bolt is provided with an eye, through which the tooth passes, 75 and the casting D is provided, at any suitable point, with a projection, I, to catch in any one of a series of notches which is made in one of the edges of the tooth, for the purpose of holding the tooth in any desired position into which 80 it may be adjusted. By having a number of these notches made in the edge of the tooth the tooth may be made longer or shorter, as may be desired, and after it has once been adjusted into the position it will be impossible for the 85 tooth to move up and down until the clamping-bolt has been loosened sufficiently to release the notch from this projection on the casting.

Upon the inner side of the casting, where it 90 projects above and below the edges of the angle-bar, are formed the stops O, which have their inner edges shaped as shown, so that the casting may be turned either forward or backward, and thus hold the tooth at an angle, 95 when the harrow is drawn in either direction. If so desired, these stops may be so placed that when the casting is turned in one position it will not move quite so far, and thus hold the tooth vertically to the side of the 100 beam, while if turned in the other direction it will turn farther around upon the pivotal bolt,

and thus hold the tooth at any oblique angle desired.

Each tooth being provided with a sharp and a blunt edge, so as to work from either side, 5 it has its lower end notched or recessed, as shown, so as to make two sharp and independent cutting-points, P. Where the end of the tooth is left solid, or but a single point is formed upon the tooth, it will not cut sod, hard 10 ground, corn-stalks, and other such substances, as it may pass over, and is not so well adapted for work in any way; but where two separate and distinct cutting-points are made, as here shown, the tooth will penetrate the ground 15 much more freely, especially when the teeth are drawn along at an angle, as here shown, so as to give a drawing cut.

I am aware that harrow-beams have been made out of U-shaped iron heretofore, and 20 this I disclaim. Angle-iron, such as is here shown, is not only lighter, cheaper, and equally strong and efficient, but the tooth can be applied much more readily and cheaply.

Having thus described my invention, I 25 claim—

1. In a harrow, the combination of a beam, the casting D, secured to the side of the beam

by means of the clamping-bolt F, which has an eye on its outer end for the harrow-tooth to pass through, the casting being provided with 30 stops on its inner side to catch over the edges of the beam, and which stops have inclined edges, so as to allow the tooth to be inclined in either direction, substantially as shown.

2. The combination, in a harrow, of a flat 35 iron beam, with the bolts C, having the large flat heads d, and the cross-bars which unite the beams together, the bolts being riveted to the side of the beams, and then made to pass up through the cross-bars, substantially as de- 40 scribed.

3. A harrow-tooth having a sharp cutting-edge in front and a blunt edge at its back, and having its lower end recessed, so as to form two separate and distinct cutting-points, 45 substantially as specified.

In testimony that I claim the foregoing I have hereunto set my hand this 26th day of October, 1880.

J. H. BARLEY.
